UNITED STATES PATENT OFFICE.

WILLIAM A. LOVELACE, OF LOVELACEVILLE, KENTUCKY.

WATER-GATE.

SPECIFICATION forming part of Letters Patent No. 328,897, dated October 20, 1885.

Application filed December 3, 1884. Serial No. 149,399. (No model.)

To all whom it may concern:

Be it known that I, WILLIAM A. LOVELACE, of Lovelaceville, in the county of Ballard and State of Kentucky, have invented a new and 5 Improved Water-Gate, of which the following is a full, clear, and exact description.

The object of my invention is to provide a simple, inexpensive, and efficient water-gate to prevent live-stock trespassing on adjacent 10 lands, and one which will be lifted automatically by the rising water, and so as to be clear of floating substances drifting down stream with the flood.

The invention consists in a water-gate constructed with the gate proper made in two sections hinged horizontally to each other and guided along hollow posts having bottom openings for inlet of water to lift floats held in the posts and connected to the gate to raise 15 it as the water rises, together with chains or cords connected to the hinged lower gate-section and passing over the upper gate-section and fixed to the banks of the stream or to the gate-posts at the front of the gate.

25 The invention consists, also, in particular constructions and combinations of parts of the gate, all as hereinafter fully described and claimed.

Reference is to be had to the accompanying 30 drawings, forming a part of this specification, in which similar letters of reference indicate corresponding parts in both the figures.

Figure 1 is a sectional elevation of my improved water-gate at the upstream side, and 35 Fig. 2 is a cross-sectional elevation taken on the line $x-x$, Fig. 1.

I make the water-gate proper in two sections, an upper section, A, consisting of side posts a and cross-bars a' , and a lower section, B, consisting of side posts b and cross-bars b' , and I hinge the two parts A B to each other by 40 hinges C of any approved kind.

The letters D D indicate two hollow posts or standards, which are fixed to the opposite 45 banks E F of the stream G or water-course in which the gate is to be set up, and a flume will preferably be built up at the opposite banks for some little distance at each side of the gate-posts D D—say, by setting the planks 50 H against the banks and securing them in any approved way.

The posts D D have openings d at or near their lower ends which rest on the bottom of the water course, said openings preferably facing upstream, so that the water flowing 55 downstream will enter the posts D D and raise the floats I I, which have angle-arms J J connected to them, the upper ends j of said arms J J being bent outward and extending through slots K K of the opposite posts D D and connected to the lower ends of the opposite side bars $a a$ of the upper gate-section A, and L L are guide studs or blocks fixed higher up on the gate-bars $a a$, and also entering the slots K K of the posts D D, and serving with the 60 parts $j j$ of the float-arms to hold the gate-section A upright as the gate is raised and lowered by the rise and fall of the floats I I as the water rises and falls.

As seen best in Fig. 2, the gate A B is placed 70 so that its lower section, B, will swing open on the hinges C downstream or in direction of the arrow M.

To the lower ends of the side posts $b b$ of the hinged gate-section B are attached the 75 one end of chains, ropes, or cords N N, preferably chains, which pass upward to and over pulleys or sheaves O O, journaled at the tops of the side posts $a a$ of the gate-section A, and thence downward in front of the gate to connect at $p p$ with the ends of arms or brackets P P, fixed to the planking H to the opposite 80 banks of the stream or to the gate-posts.

It is evident that as the gate A B is lifted by the rising water acting on the floats I I, the 85 chains N N will be drawn upon by the gate-section A, and the connections at P P being unyielding or fixed, the lower gate-section, B, will be swung back by the pull of the chains, so that its lower edge or cross-bar shall always be lifted a sufficient distance above the 90 surface of the rising water to allow drift-wood or other substances usually carried downstream by floods to pass along beneath the gate without striking and injuring it; and as the 95 flood subsides and the water falls the floats I will fall and the gate with them, and the lower gate-section, B, will gradually close into line with the upper gate-section, A, as will readily be understood.

By connecting the chains N N to section B, nearer to or farther from the hinges C, the 100

section B will be swung open quicker or more slowly, as may be required in any particular locality, to be lifted above the substances usually floated downstream by the flood.

5 I show the side posts D D made of four boards or planks nailed together and stood on end; but the posts may be made of sheet or cast metal, and in round or other form, with the water-inlets at or near their lower ends, and 10 the guide-slots for the upper gate-section, A.

The drawings represent the water-gate, set in the stream or water-course next to a fence, consisting of posts R and wires S strung on the posts, so that cattle or live-stock cannot 15 pass either way, up or down stream, to trespass on neighboring lands.

The gate-sections may be made of wooden posts and cross-bars, as seen by section A, or of wooden posts and wood and metal cross-bars, 20 as seen by section B, or of any other suitable light and strong materials.

It will be understood that the chains N may be attached to the gate-posts D near the pulleys O by brackets P or otherwise, so that the 25 connections of chains N at the front of the gate shall always be above high-water mark, to prevent the chains being carried away by floating objects, and thus disabling the gate.

Having thus described my invention, what 30 I claim as new, and desire to secure by Letters Patent, is—

1. In a water-gate, the combination, with hollow posts having bottom openings, of a vertically-sliding gate composed of two hinged sections, floats in the said posts, and connected to the upper gate-section, and means for swinging backward the lower gate-section as the gate is lifted by the floats, as set forth. 35

2. In a water-gate, the combination, with hollow posts having bottom openings, of a 40 gate composed of two hinged sections guided on the posts, floats in the said hollow posts, and connected to the upper gate-sections, and chains connected to the lower gate-section, passing over the upper section, and secured to 45 a fixed support, substantially as herein shown and described.

3. The combination, in a water-gate, of the gate-sections A B, hinged to each other at C, the hollow posts D, having bottom openings d 50 and slots K, and the floats I, moving in posts D, and connected by arms J with the side posts a a of the upper gate-section, A, substantially as herein set forth.

4. The combination, in a water-gate, of the 55 gate A B C, posts D, having openings d, and slots K, floats I, arms J, passing through the slots K, and connected to the gate-posts a, and the guide-studs L on the posts a, also entering the slots K, substantially as herein set forth. 60

5. The combination, in a water-gate, of the gate A B C, the posts D, having openings d and slots K, the floats I, connected by arms J to the gate-section A, the guide-studs L, and the chains N, connected to gate-section B, passing 65 over pulleys O at the top of gate-section A, and fastened to the banks or to the gate-posts at the front of the gate, substantially as herein set forth.

WILLIAM A. LOVELACE.
